UNITED STATES PATENT OFFICE.

ANGUS MCKENZIE, OF JAMESTOWN, NEW YORK, ASSIGNOR, BY MESNE ASSIGNMENTS, TO U. S. STANDARD VOTING MACHINE CO., OF ROCHESTER, NEW YORK, A CORPORATION OF NEW YORK.

VOTING-MACHINE.

No. 853,822.

Specification of Letters Patent.

Patented May 14, 1907.

Application filed July 25, 1898. Serial No. 686,799.

To all whom it may concern:

Be it known that I, ANGUS MCKENZIE, a citizen of the Dominion of Canada, residing at Jamestown, in the county of Chautauqua, in the State of New York, have invented certain Improvements in Voting-Machines, of which the following is a specification, reference being had to the accompanying drawings.

My present invention relates more particularly to means for preventing the voters from voting more than once for any candidate who is nominated in a group by one party, and is also indorsed by another party.

My invention also relates to certain other improvements in voting machines,—all of which improvements are fully described and illustrated in the following specification and the accompanying drawings,—the novel features thereof being specified in the claims annexed to the said specification.

In the accompanying drawings representing a voting machine containing my present improvements,—Figure 1 is a front view of a part of the key-plate. Fig. 2 is a rear elevation of a portion of machine, showing the interlocking mechanism, the straight-ticket voting-mechanism, and my improvements for preventing voting twice for an indorsed candidate. Fig. 2^a is a detail view, partly in section, showing a straight ticket lever. Fig. 3 is a sectional elevation. Fig. 4 represents one of the abutments in the interlocking mechanism. Fig. 5 represents the star-pinion and the vibrating segment. Fig. 6 represents the bell-crank lever of the irregular voting-mechanism detached. Figs. 7 and 8 are elevations of the interlocking mechanism, showing my improvements for preventing voting twice for an indorsed candidate. Fig. 9 represents a modification of the same. Fig. 10 is an enlarged view of a portion of the interlocking mechanism with the loop on the interlocking rods. Fig. 11 represents the same in a different position. Fig. 12 is a section on the line 12—12, Fig. 10. Fig. 13 is a section on the line 13—13, Fig. 11. Fig. 14 is a section on the line 14—14, Fig. 9. Fig. 15 is a section on the line 15—15, Fig. 8.

My present improvements may be used in connection with voting machines of several different types, but in the accompanying drawings I have represented them as applied

to a machine having a series of counters A A¹ A² . . . provided with the operating keys or levers B B¹ B² . . . These counters are supported in any suitable manner within a suitable casing and the key-levers project through the key-plate C in slots which permit them to be pulled downward, as indicated by the full and dotted lines on the upper counter A in Fig. 3. The key-plate is preferably recessed behind the front E of the machine.

D is a vertical plate arranged longitudinally within the casing, and to which the transverse vertical plates F, Figs. 1 and 2, are secured. The plates F support the rods G and H, which sustain the counters and the vibrating segments I I¹ I² . . ., although any other suitable arrangements for this purpose may be adopted. It will be observed that the counters are on one side of the main-plate D, and the interlocking mechanism on the other. The segment I is provided with teeth or pallets, a and b, Fig. 5, which engage with the teeth e of the four-toothed pinion J and impart to it a partial rotation on the rod G at each vibration of the segment. The pinion J is attached to a gear d, Fig. 3 which engages with a ring of teeth on the first or units disk K, Figs. 1 and 2, and this on completing a revolution, turns the next or tens disk K¹, Figs. 1 and 2, a tenth of a revolution by the partially mutilated gear d¹, Fig. 2. In Fig. 2 the main-plate D is shown as partially broken away to display one of the counters beyond it. A circular plate f is placed between the pinion J and the gear d and rotates with them,—its edge projecting over the opening in the segment. The hundreds disk is operated from the tens disk, by another similar arrangement of gears, d², Figs. 2 and 3. Thus arranged the counter will handle 999 votes, which is more than enough for ordinary districts, which rarely contain more than 600 voters. The key-levers are preferably so connected with the segments that they may be folded in inside of the key-plate for any counters which are not in use at any election. Such arrangement is indicated by the dotted lines in Fig. 5,—or the keys not used may be removed entirely.

L is a movable shutter or series of shutters used to close the openings g, Fig. 1 in the key-plate, through which the counters are in-

spected to ascertain the vote at the close of an election. At the upper left hand corner of Fig. 1, the shutter is omitted, so as to display the counter set at zero for the commencement of an election. Any suitable means is employed for moving the shutter, which is provided with openings which register with the openings in the key-plate.

Provision is made for handling the irregular vote by the slides M, Fig. 3, which are provided with the openings N, into which the ballots (inclosed in a suitable ballot-holder) are inserted by the voter, who then pushes the slide in, allowing the ballots and ballot-holders to drop down into the bags or other suitable receptacles O, from which they are removed and the irregular vote counted at the end of an election. P is a folding door which is locked to protect the irregular vote while an election is going on.

The vibrating segments I are provided with the arms h which extend through slots in the supporting plate D, and are connected to the interlocking rods R, which are suitably beveled and engage with the interlocking blocks i. Any suitable form of joint may be used between the arms h and the interlocking rods. The interlocking blocks are supported in any suitable way so as to be movable laterally, as by the race-way formed by the plates j k, which are sustained from plate D in any suitable manner. The plate j is attached to the plate D and the plate k is supported by a bracket shown at x, Fig. 3. The ends of the interlocking blocks and the abutments are slotted to fit on the opposing edges of the plates forming the race-way. Each of the interlocking rods is provided with a locking dog l, which, when the rod is raised, engages with the rock-shaft Q, as indicated by the dotted lines l¹ in Fig. 3, to hold the rod in the elevated position. The irregular slide M is interlocked with the counters, by means of the rod R¹, which is moved lengthwise when the slide is pushed in by the bell-crank lever S, Figs. 3 and 6, which is pivoted on the rod T, supported by suitable standards U Fig. 2, attached to the plate D. An arm V reaches back from the irregular slide, and receives the pivot W of the bell-crank lever S in a slot. The lever S has at its other end a pin X which engages in a slot in a plate Y attached to the end of the interlocking rod R¹. Both the arm V and the plate Y are slotted to permit of their movements at right angles with the rod T. On pushing in one of the irregular slides, the ballot-holder in the opening N falls down through a hole in the base into the bag O, the bell crank lever S is turned on the rod T, the interlocking rod R¹ is moved relatively to the interlocking blocks, the wedge on it fills the space between the stationary abutments c c¹, Fig. 2, in the interlocking mechanism, thus preventing the use of any of the counters in the same vertical line,

and the dog l engages over the rock-shaft Q, as indicated by the dotted lines l¹ in Fig. 3, and the parts are then held in this position, until the voter on leaving the voting compartment passes through the door or turnstile and by moving it restores the machine to its normal position,—the rock-shaft returning to its former place and the restoring bar Z descending and forcing the interlocking rods down, if necessary,—thus pushing the slide M outward again. It will be understood however that any other suitable irregular voting device may be used and that any other suitable connections between the irregular voting device and the interlocking rod may be adopted.

The restoring bar Z receives its motion from the shaft C¹, Fig. 2, of the door or turnstile in any suitable manner, such for instance as the cam D¹, the reciprocating bar E¹ and the bell-crank levers F¹. The rock-shaft Q is operated from the restoring bar Z by the link G¹ and crank H¹,—the rock-shaft being turned so as to release the dogs at l¹ before the bar Z acts on the interlocking rods. The rock-shaft Q is supported in suitable journals J¹, attached to the side casing or other suitable part. The interlocking rods of the counters are in a similar manner released and restored to normal position by the bar Z.

w, Fig. 2, represents slots in which the pins on the restoring bar slide,—which pins connect the restoring bar with the levers F¹.

y, Fig. 3, is a rod which runs along the back of the locking dogs l, and which may be used to insure their engagement with the rock-shaft Q,—being supported by arms z, so that it may yield upward slightly.

v is a fixed rod extending across the machine between the locking dogs and the interlocking rods.

In order to arrange the machine for a group of two candidates nominated by each party for any particular office, the abutments c c¹, Figs. 2, 7 and 8, are held stationary, while the intermediate abutment c² is allowed lateral movement. Then the voter can operate one counter in each of the vertical rows marked 7 and 8, or two counters in either of these rows, that is, he has his absolute choice among the twelve candidates, (if there are six parties and each party nominates two candidates,) but he can only vote for two and the machine automatically cuts him out from voting for any more. Thus in the instance shown in the drawings, Fig. 1, he can vote in line 7 for Stewart on counter 12, and for Fulkerson, in line 8, on counter 17, and then the interlocking rods have occupied with their wedges all the space between the fixed abutments c and c¹, and no more counters can be actuated, because no more interlocking rods with their bevels can be inserted between the interlocking blocks

i, which are arranged in any convenient way so as to be laterally movable. Similarly the voter can vote for any two candidates in vertical line 7, or any two in line 8, but he has then gone to his limit in the group. But in the practical use of voting machines at elections, the case occurs frequently,—and it may be said generally,—when a candidate, Stewart, for instance, is nominated by one party in a multicandidate group, and indorsed by another party, in which case Stewart's name will appear twice on the keyboard in that group and as a candidate for that office with a separate voting device in connection with each occurrence of his name, so that he can then be voted for by either or both of the voting devices assigned to him. As under the election laws generally in force no voter is permitted to vote more than once for any one candidate, it is indispensable that the voter be prevented from voting twice for this particular candidate, although the voter must still be permitted to vote for this candidate and some other candidate in the same group if he so desires, and having voted for any two candidates, including Stewart if he wishes, he must then be prevented from voting for a third. It also happens that in the same group another candidate, Fulkerson, in the instance shown, which has actually occurred in my experience, is nominated by one party and indorsed by another. This case must also be provided for, so that no voter can vote twice for Fulkerson, while, after having voted for Fulkerson on either counter he must be at liberty to vote for any other candidate in the group.

In order to prevent a voter from voting twice for Stewart, who in the instance shown is nominated by the Democratic party on counter 12, and indorsed by the National Democratic party on counter 13, I lock the corresponding interlocking rods, R^{12} and R^{13} , Fig. 2, together, so that both cannot be used to operate their respective counters. The link, clamp or loop, m , Fig. 2, secures this result. Either of the interlocking rods R^{12} or R^{13} may be inserted in the interlocking mechanism,—the loop permitting either to be used. But the loop m will prevent both being used, because it will not allow the rods to spread sufficiently so that both rods can be inserted between the interlocking blocks. And this action of the loop or connecting device is entirely independent of the direction of their movement of the rods, whether it be a push on them, a pull, or whether they be vertical or horizontal or arranged at any angle. By locking the interlocking rods of the counters of any candidate nominated twice, by means of the loop m , I prevent any voter from voting for such candidate twice.

The operation of the loop in preventing

voting for an indorsed candidate will be 65 readily understood from the rod equal to Figs. 10, 11, 12 and 13. The loop m is attached at one end n to one of the interlocking rods, while its other end o stands at a distance from the other rod equal to the thickness of the wedge p . When the counter corresponding to interlocking-rod R^{12} is actuated, the wedge P on the rod enters between the interlocking blocks i , (see Fig. 11) and the rod shifts laterally so that it brings the 70 bent end o of the loop m into contact with the interlocking rod R^{13} ,—after which the counter corresponding to rod R^{13} can not be operated, because its wedge p can not get in between the blocks i without moving the rod 80 laterally, which the loop prevents. Since the rods R^{12} and R^{13} correspond to the counters of the indorsed candidate Stewart, it will be impossible to vote twice for him, although his name appears twice on the key-plate. A 85 voter can vote for Stewart on either counter, but such vote prevents voting for him on the other counter, on which his name appears. If the loop is attached to one of the rods, it will move with that rod,—the end o sliding 90 on the other rod. The rod R^{13} when moved, slides through the loop, without affecting the other rod. A similar loop, m^1 , Fig. 2, is applied to the rods R^{17} R^{18} to prevent voting twice for the candidate Fulkerson, who is 95 nominated and indorsed on counters 17 and 18, Fig. 1.

The loops may be made in any suitable way, and they may be located in any suitable position on the rods. Thus in Fig. 9, I 100 have represented the loop m^2 as placed over the thinned portions of the interlocking rods,—the form of the loop being given in Fig. 14. The wedges may be given any desired amount of obliquity or abruptness, and 105 they may be rounded or otherwise shaped,—even a square shoulder working very well with round interlocking blocks.

In applying this special device to preventing voting for an indorsed candidate more 110 than once, it will of course be understood that the indorsed candidates are not thereby eliminated from the group. The application of this device creates a group within a group, or creates a small sub-group within a large 115 main group. To make the relation of the parts more clear, I will explain that in the present case, Stewart has been nominated twice, and either of two keys or voting devices may be used in voting for him, and these voting devices are specially controlled so that while the voter may choose between each of these voting devices, he cannot operate both of them. If he votes for two candidates other than Stewart, he is thereby prevented 120 from voting for Stewart at all, the voting devices for Stewart being to that extent and for that purpose included in the

main group, it being understood that the main group permits the operation of any two of all the voting devices included therein and no more.

5 The auxiliary device does not in any way interfere in this respect with the operation of the main interlocking device, but supplements it, in that while the main interlocking device would otherwise permit the operation 10 of both of Stewart's voting devices and would while both of Stewart's voting devices were operated prevent the operation of any other voting device in the group, in this instance the operation of one of Stewart's voting devices prevents the operation of the other one of them through the sub-grouping device and through the main grouping device, after a second voting device has been operated therein for another candidate, the 15 voting for Stewart above mentioned also prevents the operation of a third voting device in the large group, which might have been voted in its stead. It is, of course, open to operate two voting devices in the group for 20 any candidate other than Stewart, and when 25 two votes have been so cast, the voting for Stewart is prevented.

In Fig. 2, it will be observed that the interlocking rods are offset in each direction from the row of arms h , and that the wedges are 30 double,—one on each side of the rod. In Figs. 7 and 8, the interlocking rods are offset in the same direction from the arms, and they are shown in Fig. 7 with double wedges 35 and in Fig. 8, with single wedges,—that is the thicker portions project in one direction only. In Fig. 8, I have also shown the loops as applied to three or more interlocking rods, so as to provide for the case where a candidate is indorsed two or more times,—as indicated with reference to Ferris, line 9 of Fig. 1, who is nominated on counters 23, 24 and 40 25. The loop m^3 embraces four rods, but it will be seen that in action it only affects the rods $R^{23} R^{24} R^{25}$, which correspond to the 45 counters on which Ferris is nominated and twice indorsed. The rod R^3 controls the movement of the interlocking block i^1 , but can itself be worked after the use of any one 50 of the other three. When the rods are close together, they may be thinned for the application of the loops. m^4 Fig. 8, represents another longer loop, which permits the handling of a still greater number of indorsements.

55 It has already been stated that a group of two candidates is formed by allowing lateral movement in the central abutment c^2 , Figs. 2 and 7. In a similar manner the machine is 60 adapted to larger groups by allowing two or more of the adjacent abutments to move laterally on the ways j k . Thus for a group of three, two adjacent abutments are left movable, and so one for any larger group,—the

abutments at the ends of the group remain- 65 ing stationary. Provision may be made for these changes in any suitable way. In the construction shown, the abutments are fastened to the ways by the staples q , Figs. 2, 4 and 7 which pass through holes in the abutments and engage in openings in the way. To render an abutment movable, it is only necessary to remove its pin or staple, and it is fixed stationary by again inserting the same. The groups vary in number and in 70 the number of candidates from one election to another and the indorsements are of course very variable, but my present improvements are applicable to any number of groups and to groups of any number, and to any number 75 of indorsements, as already explained. In the accompanying drawings, Fig. 1, I have shown two groups, one of two candidates, and one of three candidates, but it will be understood that my machine is constructed so 80 as to allow of any required number of groups of any required number of candidates, and that it can be adjusted so as to permit single candidate voting on any of the vertical lines of counters. The groups are thus not only 85 interchangeable with the single-candidate voting mechanisms, but they may be regrouped in any desired manner or in any desired position on the key-plate.

90 In using groups, I connect the irregular 95 slides together and close the opening in all but one of them. Thus for a group of two, indicated by lines of counters 7 and 8 in Fig. 1, I attach the irregular slides $M^7 M^8$ together by the strap L^1 , so that they will both be pushed 100 in together, and I close the opening N , Fig. 3, in one of them in any suitable way, and thus I prevent voting in more than one of the irregular slides. When the two slides $M^7 M^8$ are pushed in, their interlocking rods are inserted between the interlocking blocks of the 105 group, so that none of the counters in the group can be actuated.

110 The opening N in one of the slides may be closed in any convenient way, as by the plate r , Fig. 3. The slides may be connected together in any suitable manner, and the connection may be placed behind the key-plate, if preferred. When the machine is set for 115 single candidate voting, the connection between the slides is removed. For a group of three, the three irregular slides $M^9 M^{10} M^{11}$ are fastened together, by the bar L^2 or other suitable connection and the openings in two 120 of them are closed. Groups of larger numbers are treated in the same way. In this manner the voter is prevented from using the irregular slides of a group to deposit more than one ballot.

125 For voting straight, the levers $S^1 S^2 S^3 \dots$ Fig. 1, are provided, which operate the bars $T^1 T^2 T^3 \dots$, Figs. 2 and 3, and the motion of these bars is transmitted by the bell-crank

levers u , Fig. 2, to raise the arms h , so as to actuate all the counters in any one horizontal row,—which counters represent all the candidates of any particular political party. The movement of one of the bars T and its set of bell-cranks is indicated for the bar T^1 by full and dotted lines in Fig. 2. On voting a straight ticket, one interlocking rod in each vertical line of counters is actuated, and so voting on any of the other counters is prevented. At the same time, the loops do not interfere in any way with straight-ticket voting, since the looped rods are free to move independently of each other. The bars are provided with a series of pins, t , which act against the ends of the bell-crank levers, which are pivoted at s to a series of studs on the main plate D . The other ends of the levers bear underneath the counter-lever arms h ,—so that the arms are permitted to rise independently of the levers. The straight-ticket levers $S^1 S^2 S^3 \dots$ exercise a pull on the bars $T^1 T^2 T^3 \dots$ in operating a row of counters. These straight ticket levers are bent or offset, so as to bring their free ends and the slots in the key-plate in which they work, opposite to the centers of the row of counters to which they correspond. When a straight-ticket has been voted, the restoring bar Z , acting on the interlocking rods, returns the straight - ticket lever to normal position through the bell-crank levers. The straight-ticket levers are pivoted on a shaft U^1 , Fig. 2, supported by suitable brackets V^1 . W^1 are thimbles inserted between the brackets and levers to hold the latter in place. The levers $S^1 S^2 S^3 \dots$ engage in notches in the bars $T^1 T^2 T^3 \dots$, so that the bars are operated by the movements of the levers. Bars or clips N^1 , Fig. 2, are used to attach the straight-ticket bars T to the main-plate. It will of course however be understood that any other suitable type of straight-ticket mechanism may be employed, that the bars may either push or pull, or that rock-shafts may be used for actuating all the counters in any one horizontal row, corresponding to a political party.

The counters K are operated by the movement of the key levers B , B^1 , etc., and the resetting bar Z —partly by the lever and partly by the resetting bar. On pulling down the lever B , the tooth a on the segment I engages one of the teeth e on the pinion J , moving it a part of a revolution, and by means of the connecting gearing partially operating the counter K . The last part of the movement of the counter is effected by the restoring or resetting bar Z , which acts through the interlocking rods to return the segment I to its normal position, as shown in Fig. 3, the tooth b on the segment I engaging one of the teeth e on the pinion J , finishing the movement of the counter. The parts named can, of course, be so arranged that half or any part of the move-

ment of the counter may be effected by the lever B and the rest by the resetting mechanism or the whole movement by the lever B or by the resetting mechanism.

Of course it is evident that many modifications of the various parts shown in the drawings may be issued without departing from the spirit of my invention, and I wish it to be expressly understood that I do not limit myself to the features shown and described, but desire to have this application cover generally any means for preventing a voter from voting twice for an indorsed candidate.

My present improvements are applicable to a case where a candidate, nominated on counter 12, is indorsed on counters 14 or 15, by a proper arrangement of the interlocking rods.

I claim.

1. In a voting machine, the combination of multicandidate group voting mechanism, with means for preventing a voter from voting more than once for a candidate whose name appears upon two or more of the lists of candidates for the same office, nominated by the different political parties.

2. In a voting machine, the combination of multicandidate group voting mechanism, in which two or more keys can be operated by each voter, with means for preventing a voter from operating more than one of the keys, which are used in connection with the name of a candidate appearing two or more times on the list of candidates.

3. In a voting machine, the combination of multicandidate group voting mechanism, and means for interlocking the particular counting mechanisms representing a candidate who is nominated for the same office by two or more political parties, whereby each voter will be prevented from voting more than once for such candidate.

4. In a voting machine, the combination of multicandidate group voting mechanism, of detachable means for preventing a voter from voting more than once for a candidate nominated by two or more political parties.

5. In a voting machine, the combination with multicandidate group voting mechanism, and detachable and adjustable means for preventing a voter from voting more than once for a candidate nominated by two or more political parties, whereby said result will be attained, no matter where the name of the candidate who is nominated more than once appears in the series of nominations for the same office.

6. In a voting machine, the combination with multicandidate group voting mechanism, consisting of two or more series of interlocked voting mechanisms, two or more of which voting mechanisms represent the same candidate, and means detachably connected to the voting mechanisms which represent

the same candidate, for preventing a voter from actuating more than one of said voting mechanisms.

7. The combination with the multicandidate group voting mechanism of a voting machine, of detachable means for preventing voting more than once for a candidate nominated by two or more political parties, and suitable interlocked irregular voting mechanism.

8. The combination with the multicandidate group voting mechanism of a voting machine, of detachable means for preventing voting more than once for a candidate nominated by two or more political parties, and straight ticket voting mechanism.

9. The combination with the multicandidate group voting mechanism of a voting machine, consisting of two or more series of interlocked voting mechanisms, two of which voting mechanisms represent the same candidate, of means independent of all except the members of said group for preventing a voter from actuating both of said voting mechanisms, and suitable interlocked irregular voting mechanism.

10. The combination with the multicandidate group voting mechanism of a voting machine, of means for preventing voting more than once for a candidate nominated twice, suitable interlocked irregular voting mechanism, and suitable straight ticket voting mechanism, whereby all the voting devices in the group belonging to any one political party may be actuated.

11. The combination with the multicandidate group voting mechanism of a voting machine, consisting of two or more series of interlocked voting mechanisms, two of which voting mechanisms represent the same candidate, of means for preventing a voter from actuating both of said voting mechanisms, and suitable straight ticket voting mechanism.

12. In a voting machine, the combination with the group voting mechanism, comprising two or more series of two or more voting mechanisms in each series, suitable actuating means for said voting mechanisms, suitable interlocking mechanism between the voting mechanisms of each series, and suitable supplementary interlocking mechanism between two or more of the voting mechanisms in the same series.

13. The combination, in a voting machine, of the interlocking rods of two or more series of two or more voting mechanisms in each series, the interlocking blocks for each series, an abutment between the series, means for rendering the abutment movable or stationary, and suitable supplementary interlocking mechanism between two or more of the voting mechanisms in the same series.

14. The combination, in a voting machine,

of variable multicandidate group voting mechanism interchangeable with single candidate voting mechanism, such mechanism comprising two or more series of voting mechanisms, suitable actuating devices therefor, interlocking devices and supplementary interlocking devices between two or more voting devices representing the same candidate for preventing a voter from voting more than once for a candidate nominated for the same office by two or more political parties.

15. In a voting machine, the combination of multicandidate group voting mechanism consisting of counters, actuators adapted to be operated by a voter, and positively actuated means for positively returning said actuators and thereby completing the actuation of the selected counters with means for preventing each voter from voting more than once for a candidate nominated by two or more political parties.

16. In a voting machine, the combination of multicandidate group voting mechanism, means for preventing voting more than once for a candidate nominated by two or more political parties, and suitable irregular voting mechanism interlocked with said multicandidate group voting mechanism, the actuating devices of said irregular voting mechanism being locked together.

17. In a voting machine, the combination of multicandidate group voting mechanism, detachable means for preventing voting more than once for a candidate nominated by two or more political parties, and suitable irregular voting mechanism interlocked with said multicandidate group voting mechanism, the actuating devices of said irregular voting mechanism being locked together.

18. The combination with the multicandidate group voting mechanism of a voting machine, consisting of two or more series of interlocked voting devices, two of which voting devices represent the same candidate, of means independent of all except the members of said group for preventing a voter from actuating both of said voting devices, suitable interlocked irregular voting mechanism and means for locking the actuating parts of said irregular voting mechanism together.

19. The combination with the multicandidate group voting mechanism of a voting machine, of means for preventing a voter from voting more than once for a candidate nominated twice, suitable straight ticket voting mechanism, suitable interlocked irregular voting mechanism and means for locking the actuating parts of the irregular voting mechanism together.

20. In a voting machine, a multi-candidate voting mechanism including two or more single candidate voting mechanisms arranged in different party rows or columns

for voting for the same candidate, and means for preventing the voting at one time of more than one of the single candidate voting mechanisms.

5 21. In a voting machine, the combination, in a multicandidate group, of a series of counters, the actuators of two or more of which are connected in operation, with suitable interlocking mechanism between said counters and the other counters of said group.

22. In a voting machine, the combination in a multicandidate group devoted to candidates for the same office and arranged in parallel rows, of two or more counter actuating mechanisms and means controlling the operation of said mechanisms so only one vote can be registered by said mechanisms (until after the machine is reset) by any one of said actuating mechanisms.

23. In a voting machine, the combination of a main interlocking mechanism, a plurality of movable parts interlocked thereby, said interlocking mechanism, limiting the operation of said movable parts to a predetermined number more than one, and an auxiliary interlocking mechanism, interlocking a portion of the same movable parts which are interlocked by the main interlocking mechanism, and limiting the operation of the parts controlled thereby to a predetermined number, which number is less than what would otherwise be permitted by the main interlocking mechanism.

35 24. In a voting machine, the combination in a multicandidate group, of a main interlocking mechanism, a plurality of movable parts interlocked thereby, said interlocking mechanism limiting the number of said movable parts that may be operated; but permitting the operation of more than one of said parts, and an auxiliary interlocking mechanism interlocking a portion of the same movable parts which are interlocked by the main interlocking mechanism and still further limiting the number of parts that may be moved.

25. The combination with the multicandidate group voting mechanism of a voting machine comprising a separate voting device for each candidate, any two of which in any one office line may belong to the same candidate, of separate straight ticket voting mechanism for each party, whereby all the voting devices in the group belonging to any one political party may be simultaneously placed in voted position, and means for preventing voting more than once for a candidate that can be voted for by either of the straight ticket voting mechanism of two or more parties.

60 26. The combination with the multicandidate group voting mechanism of a voting machine, of separate straight ticket voting

mechanism for each party, whereby all the voting devices in the group belonging to any one political party may be simultaneously placed in voted position, and means for preventing voting more than once for a candidate that can be voted for by either of the straight ticket voting mechanism of two or more parties.

27. The combination with the multicandidate group, voting mechanism of a voting machine, of means for preventing voting more than once for a candidate nominated twice, and suitable straight ticket voting mechanism for each party, whereby all the voting devices in the group belonging to any one political party may be simultaneously placed in voted position.

28. In a voting machine, the combination of a plurality of single candidate groups of voting devices, each single candidate group comprising one irregular device for voting for candidates not nominated, and a plurality of keys and counters for voting for regularly nominated candidates, said voting devices being suitably interlocked to prevent the voting of more than one of said devices in a single candidate group, said single candidate group being interchangeably related for accurate multicandidate group voting, and means, when a plurality of single candidate groups are combined in one multicandidate group, for connecting all the irregular balloting devices in said multicandidate group for simultaneous voting operation and preventing the separate voting operation of any one of them whereby the operation of any or all of them is prevented by the interlocking mechanism and the connecting means if one of the regular voting devices has been operated.

29. In a voting machine, the combination of a plurality of single candidate groups of voting devices, each single candidate group comprising one irregular device for voting for candidates not nominated, and a plurality of keys and counters for voting for regularly nominated candidates, said voting devices being suitably interlocked to prevent the voting of more than one of said devices in a single candidate group, said single candidate group being interchangeably related for accurate multicandidate group voting, and means, when a plurality of single candidate groups are combined in one multicandidate group for preventing the casting of a vote by the irregular voting devices of a group if one of the regular voting devices of a group has been placed in voted position.

30. In a voting machine, multicandidate group voting mechanism comprising a plurality of keys suitably interlocked to prevent the voting of more than a predetermined number of said keys less than the whole, two or more of said keys being operable to vote for the one and the same candidate, means to

prevent voting for said candidate more than once, said means permitting the voting operation of either of the keys belonging to said candidates.

31. In a voting machine, multicandidate group voting mechanism comprising voting devices all capable of voting operation but suitably interlocked to limit the number of all of said voting devices that may be in voted position at the same time, two or more of said voting devices belonging to the same candidate and an auxiliary means limiting the operation of the voting devices belonging to said candidate so that but one vote may be cast thereby.

32. In a voting machine, the combination of a main interlocking mechanism, a plurality of voting devices interlocked thereby, said interlocking mechanism limiting the operation of said voting devices to a predetermined number more than one, and permitting the operation of two of said voting devices that may belong to the same indorsed candidate, thereby making it possible to vote for said indorsed candidate twice, and an auxiliary interlocking mechanism interlocking only the voting devices belonging to said indorsed candidate and preventing voting twice for the said indorsed candidate without disturbing the relation between the voting devices of the indorsed candidate and the other voting devices included in the group.

33. In a voting machine, the combination of a multicandidate group voting mechanism that limits the total number of voting devices that can be voted in a group and that permits voting twice for an indorsed candidate therein, and an indorsing device that prevents voting twice for the said indorsed candidate without disturbing the relation between the voting devices of the indorsed candidate and the other voting devices included in the group.

34. In a voting machine, the combination of a multicandidate group voting mechanism including a plurality of voting devices for individual candidates suitably interlocked to limit the operation of said voting devices to a predetermined number and permitting the operation of two of said voting devices that may belong to the same indorsed candidate, thereby making it possible to vote for said candidate twice, and an indorsing device that prevents voting twice for the said indorsed candidate without disturbing the relation between the voting devices of the indorsed candidate and the other voting devices included in the group.

35. In a voting machine, the combination of a multicandidate group voting mechanism including a plurality of voting devices for individual candidates suitably interlocked to limit operation of said voting

devices to a predetermined number and permitting the operation of two of said voting devices that may belong to the same indorsed candidate, thereby making it possible to vote for said indorsed candidate twice, and an indorsing device that preserves the proper relation between the voting devices of the indorsed candidate and the other voting devices included in the group, and prevents voting twice for said indorsed candidate.

36. In a voting machine, the combination of a plurality of voting devices embodying indicators and registers, a limiting mechanism for preventing the operation to voted position of more than a predetermined number of the whole number of indicators, and connections between a limited number of said devices for permitting the registration of a single vote only by the devices so connected when any one of their indicators is in voted position.

37. In a voting machine, the combination of a series of voting devices, a plurality of which are devoted to the same candidate, a limiting mechanism for preventing more than a predetermined number of the whole from occupying voted position at the same time and connections between the devices devoted to the same candidate for permitting the registration of a single vote only when any one of said devices is in voted position.

38. In a voting machine, the combination of a plurality of voting devices embodying registers, and separately operable by the voter, a limiting mechanism for permitting the registration of a predetermined number of votes less than the whole number of voting devices, mechanism controlling the operation of the registers of a predetermined number of said devices less than the whole number and forming them into a sub-group, the operated devices in the sub-group coöperating with the limiting mechanism first mentioned to permit only the proper aggregate number of votes to be registered.

39. In a voting machine, the combination of a plurality of voting devices, a limiting mechanism for preventing the operation to voted position of more than a predetermined number of the whole, and connections between a number of voting devices less than the whole, forming a sub-group and operating to cause the registration of a single vote by the operation of any one of the sub-group of devices.

40. In a voting machine, the combination of a plurality of voting devices embodying registers and separately operable by the voter, a limiting mechanism controlling a portion of said devices forming a sub-group and permitting the operation to voted position of a predetermined number thereof, and a limiting mechanism preventing the operation to voted position of more than a predetermined number of the whole, and connections between a number of voting devices less than the whole, forming a sub-group and operating to cause the registration of a single vote by the operation of any one of the sub-group of devices.

mined number of the whole number of devices.

41. In a voting machine, the combination of multicandidate group voting mechanism, with means for preventing a voter from voting more than once for a candidate nominated two or more times by the different political parties whose name correspondingly

appears upon two or more of the lists of candidates for the same office with a separate voting device for each appearance of his name.
